UNITED STATES PATENT OFFICE.

WILLIAM H. SHUGART, OF NEWPORT, TENNESSEE.

RAIL-JOINT.

937,333.

Specification of Letters Patent. Patented Oct. 19, 1909.

Application filed June 26, 1909. Serial No. 504,494.

To all whom it may concern:

Be it known that I, WILLIAM H. SHUGART, a citizen of the United States, residing at Newport, in the county of Cocke and State of Tennessee, have invented certain new and useful Improvements in Rail-Joints, of which the following is a specification.

This invention relates to railway appliances and especially to an improved form of railway rail joint having in view a device of this character which shall possess certain features of merit adapting it peculiarly to the purposes of the device and enhancing the symmetry and general appearance as well as the general utility and practicability of the device.

For a full understanding of the invention reference is to be had to the following detailed description and the accompanying drawings, in which—

Figure 1 is a diagrammatic plan view indicating a completed rail joint made in accordance with the invention; Fig. 2 is a transverse vertical section taken substantially through the device at the end of the rail; Fig. 3 is a perspective detail showing the relation between a fish plate and the chair and especially the means to lock the two said parts together; Fig. 4 is a detail perspective of one of the fish plates detached, and Fig. 5 is a sectional view similar to Fig. 2, but of a slight modified construction.

Throughout the following description and on the several figures of the drawings similar parts are referred to by like reference characters.

In carrying out this invention in the practical embodiment thereof, a chair or base plate 10 of any suitable length to rest upon two or more cross ties 11 is provided. Said chair comprises a flat base portion 10^a from which along its lateral edges extend upwardly and inwardly a pair of parallel bracing flanges 10^b. The inner faces of said flanges adjacent to the base 10^a are preferably spaced at some distance outwardly from the base flanges of the rails 12, and the upper edge of said flanges 10^b are spaced sufficiently far apart to permit the introduction of the base 12^c of the rails without slipping the chair or the rails longitudinally of each other. As indicated in Fig. 2, for instance, the rail 12 may be introduced into and upon the chair after the latter has been placed into its position by simply tilting

the rail so as to permit the base 12^c to pass into the chair. This is important for the reason that when it is necessary to replace a broken or damaged rail only the fastening devices for that rail require to be removed or loosened, the chairs at the opposite ends of the rails remaining in place.

The chair having been secured in place and the meeting rail ends introduced thereto as above described a pair of fish plates 13 of peculiar form are driven into the spaces between the web 12^a of the rails and the flanges 10^b of the chairs. The fish plates are wedge shaped or tapering from end to end and are driven into position from opposite ends of the chair. The chair therefore will occupy a slight angular position with reference to the line of the rails 12 as indicated in Fig. 1. Each fish plate wedge 13 is provided with a shoulder 13^a which rests upon the upper edge of the adjacent flange 10^b, said shoulder being formed by an undercut rabbet into which the said flange projects. The outer face of the fish plate lies substantially in the plane of the outer face of the flange, permitting a smooth and neat joint. The fish plate is comparatively broad on its base and projects outwardly beyond the rail base 12^c snugly against the inner face of the chair flange 10^b. The shoulder 13^a fitting snugly upon the edge of the flange prevents any possibility for the lateral strain or thrust of the fish plate, due to side strain on the rail 12, from spreading or distorting the joint chair.

I have found by practical experience that a difficulty heretofore existing in railway joints was due to tendency of the rails to tilt, due to improper or ineffective bracing at the joints. The construction of this invention is admirably adapted to prevent this difficulty by its peculiar interlocking and bracing construction.

The construction of Fig. 5 is substantially similar to that above described, but the chair flanges 10^c extend farther up toward the bead 12^b of the rail. The shoulder 13^c of each fish plate cooperates with the upper edge of the said flange 10^c for the same purpose as set forth.

A joint constructed and assembled as herein described will ordinarily not require auxiliary devices to prevent displacement of the parts, the friction between the fish plates and the other parts of the joint ordinarily being sufficient to retain them in position.

It is my desire, however, to provide a simple and yet effective means for positively preventing longitudinal unauthorized displacement of the fish plates. To this end I 5 provide one or both of the chair flanges with one or more notches 14 and into which the adjacent outer edge of the fish plate shoulder may be set by operation with a punch or similar tool as indicated at 15. The said 10 shoulder along its outer edge being comparatively thin is capable of being upset or swaged into said notches. This result may be accomplished by a simple operation of a tool, and when necessary to remove the fish 15 plates, a reverse operation by a chisel or the like may be resorted to to loosen the same. The chair may be held in place on the cross ties by means of spikes 16 coöoperating with notches 17 on the chair in a well known 20 manner.

Having thus described a preferred embodiment of the invention, what is claimed as new is:

1. The herein described rail joint comprising, in combination with the meeting ends of railway rails, a chair having a flat bottom receiving said rails thereupon and a pair of parallel upwardly and inwardly projecting side flanges, said flanges being spaced 25 at their bottoms at some distance outwardly from the rail base and extending upwardly and inwardly substantially in a line with the rail bead, a pair of tapered fish plates driven from opposite ends of the chair into 30 the spaces between the rails and said chair flanges, each of said fish plates having an 35 at their bottoms at some distance outwardly from the rail base and extending upwardly and inwardly substantially in a line with the rail bead, a pair of tapered fish plates driven from opposite ends of the chair into the spaces between the rails and said chair flanges, each of said fish plates having an

outwardly projecting shoulder forming an undercut rabbet into which the upper edge of the adjacent chair flange is received, the outer surface of the fish plate substantially 40 coinciding with the corresponding surface of the chair flange, and means to prevent undesirable longitudinal displacement of the fish plates.

2. The herein described rail joint comprising, in combination with the meeting ends of railway rails, a chair having a flat bottom receiving said rails thereupon and a pair of parallel upwardly and inwardly projecting side flanges, said flanges being spaced 45 at their bottoms at some distance outwardly from the rail base and extending upwardly and inwardly substantially in a line with the rail bead, a pair of tapered fish plates driven from opposite ends of the chair into 50 the spaces between the rails and said chair flanges, each of said fish plates having an outwardly projecting shoulder forming an undercut rabbet into which the upper edge of the adjacent chair flange is received, and 55 means constituting a positive lock between said fish plates and chair, said means including one or more notches formed in each of said chair flanges adjacent their upper outer edges into which portions of the fish 60 plate shoulders may be swaged.

In testimony whereof I affix my signature in presence of two witnesses.

WILLIAM H. SHUGART.
